UNITED STATES PATENT OFFICE.

JAMES W. UNDERWOOD, OF ST. LOUIS, MISSOURI.

FLASH-LIGHT APPARATUS.

939,354.

Specification of Letters Patent.

Patented Nov. 9, 1909.

Application filed February 10, 1909. Serial No. 477,247.

To all whom it may concern:

Be it known that I, JAMES W. UNDERWOOD, a citizen of the United States, and resident of St. Louis, Missouri, have invented certain new and useful Improvements in Flash-Light Apparatus, of which the following is a specification.

My invention relates to an improved flash-light apparatus, and has for its object to provide an apparatus in which calcium or like material may be securely held and certainly ignited by means of the explosion of a fulminate cap, and in which the means for exploding such cap may be automatically 15 re-set after each explosion.

In the drawings—Figure 1 is a perspective view of a device embodying my invention. Fig. 2 is an enlarged detail view of the same in side plan view. Fig. 3 is a perspective view of the trigger employed in my invention. Fig. 4 is a top plan view of the trigger mechanism, the supporting rod being shown in section along the line 4—4 of Fig. 2.

As shown in the drawings, I provide a supporting rod 5 upon the top of which is mounted a pan 6 having upturned edges 7—7; about mid-way of its length the pan 6 is provided with the firing-block 8. The screw 9 passes through an opening in the firing-block 8 and through the bottom of the pan 6 into the top of the support 5, as shown in Fig. 2. One end of the firing-block 8 contacts with the bottom of the pan 6 and is secured thereto by means of the rivet 10. The opposite end of the firing-block 8 is slightly elevated from the bottom of the pan 6 as indicated by the numeral 11; so as to admit the fulminate cap 12 being 40 inserted in place beneath the portion indicated by the numeral 11 and above the opening 13 provided in the bottom of the pan 6.

Upon the support 5 I provide a base-plate 14 upon which the trigger 15 is pivotally 45 mounted at the point 16, the spring 17 being mounted about the point 16 and having its lower extremity held by the lug 18 and its upper extremity secured in the opening 19 with which the trigger 15 is provided. The 50 base-plate 14 is extended to form the brackets 20 and 21 which are slotted as indicated by the numeral 22 to receive the hammer 23 which is in the form illustrated in Fig. 3; having a narrow elongated lower end 24 and a wider elongated upper body 25, and the trigger-rest 26; the shoulder 27 being formed

between the body-member 25 and the portion 24.

The coil-spring 28 is mounted loosely about the portion 24, its lower end being 60 secured to or resting upon the upper face of the bracket 21, and its upper end being held in place against the shoulder 27. The upper face of the body 25 is adapted to pass through the opening 13 and the base of the pan 6 to 65 strike and explode the fulminate cap 12 and thereby ignite the flashlight material contained in said pan.

The trigger 15 is provided with an exploding cord 29 terminating in a ring 30 at 70 its lower end and being attached to the trigger 15 by being passed through the opening 19.

The hammer 23 is normally in the position illustrated in Fig. 1, the projection 31 of the 75 trigger 15 resting in place upon the shoulder 26 of the hammer 23; the downward pull upon the cord 29 permits the cap 12 to be seated in place and by continuing said pull the trigger 15 is still further depressed, 80 drawing with it the hammer 23, until the point 31 is disengaged from, and releases the hammer 23, which, thereupon, is driven upward by the spring 28 to discharge the cap 12. The cord 29 being released, the trigger 85 15 is carried upwardly by means of the spring 17 and again seated in place upon the shoulder 26; the pivotal connection between the trigger 15 and the base-plate 14 at the point 16 being of such a character as to permit the outward play of the point 31 over the shoulder 26, as illustrated by the dotted lines in Fig. 4; the spring 17 being mounted around the body 32 to form a short coil 90 spring, as indicated by the numeral 33 in 95 Fig. 4.

Having thus fully described my invention, what I claim as new and desire to have secured to me by the grant of Letters Patent, is:

In a flashlight apparatus, the combination of a supporting rod; a pan mounted on the upper extremity of said rod; a firing-block mounted upon the upper face of the bottom of said pan, said pan being provided with a 105 perforation beneath the firing-block; a base-plate mounted on the supporting rod; a trigger loosely and pivotally mounted on the base-plate; a slotted bracket mounted on said supporting rod; a hammer slidably 110 mounted in the slots of said bracket; a spring whereby said hammer is normally held in

contact with the firing-block; a spring whereby the trigger is normally held in contact with the hammer, and whereby the trigger is restored to contact with the hammer 5 after each discharge, substantially as described.

In testimony whereof, I have signed my

name to this specification, in presence of two subscribing witnesses.

JAMES W. UNDERWOOD.
